(57) **CLAIM**

The ornamental design for electric wine opener, as shown and described.

DESCRIPTION

FIG. 1 is a top view of an electric wine opener, showing my new design;

FIG. 2 is a bottom view thereof;

FIG. 3 is a front view thereof;

FIG. 4 is a left side view thereof;

FIG. 5 is a right side view thereof, the left side view being a mirror image;

FIG. 6 is a perspective view thereof;

FIG. 7 is a rear view thereof;

FIG. 8 is an enlarged view of the portion indicated with number 8 in FIG. 3; and,

FIG. 9 is an enlarged view of the portion indicated with number 9 in FIG. 6.

The portions of the article drawn in dash-dot lines form no part of the claimed design. The dash-dot lines in FIGS. 3, 6, 8 and 9 depict the bounds of the enlarged views and form no part of the claimed design.

1 Claim, 9 Drawing Sheets
